UNITED STATES PATENT OFFICE.

ISAAC SETH HIRSCH, OF NEW YORK, N. Y.

X-RAY TUBE.

1,120,493.

Specification of Letters Patent. Patented Dec. 8, 1914.

Application filed May 15, 1913. Serial No. 787,879.

To all whom it may concern:

Be it known that I, ISAAC SETH HIRSCH, a citizen of the United States, residing at New York, in the county of New York and State of New York, have invented certain new and useful Improvements in X-Ray Tubes, of which the following is a specification.

This invention relates to X-ray devices particularly to a novel form of X-ray tube and has for its object the provision of a tube having double walls to provide an annular space for containing oil or solutions of various salts for the two-fold purpose of absorbing the heat generated and filtering the rays.

A further object is to provide a tube of this character provided with means for receiving detachable caps of various materials for further filtering the rays and also to serve as a filling orifice.

There are two parts in an X-ray tube where heat is generated, the negative pole or cathode cup from which the cathode stream rushes to the target or positive pole, and at the point where this cathode stream strikes the anode or target of the tube. This heat is carried off by both the glass of the tube and the metal parts and the slow radiation of this heat is the cause of the lowering of the vacuum in the tube which results in the generation of X rays of low penetrating power called soft rays, which have a destructive effect on the superficial human structure. By placing in said annular space between the double walls of my device an insulating substance of heat absorbing qualities I absorb the heat generated by the impact of the cathode stream against the anodal target and reflected against the inner wall of the tube and also cool the cathode of the tube, and further by the provision of detachable caps of various materials I provide means for filling said annular space and for the further absorption and filtration of any soft rays that may be generated within the tube even when it is cool.

Referring more particularly to the drawings forming part of this specification and in which like numerals are employed to designate corresponding parts throughout the several views: Figure 1 is a longitudinal sectional view through one form of the tube, parts being in elevation, and Fig. 2 is a similar view through a modified form.

Referring more particularly to the drawings, the numeral 1 designates the bulb of an X-ray tube which is provided with the usual cathode 2, anode 3, and regulating chamber or device 4 which may be of any sort desired.

Surrounding the bulb 1 and spaced therefrom is a shell or container 5 of glass which has one end 6 connected with the anode tube and its other end 7 connected with the cathode tube, as shown. It will be observed that the end 7 is spaced considerably from the cathode tube to form an annular chamber 8. A tube 9 fitted with any desired closure 10 is formed on the shell or container 5 for filling the space between the bulb 1 and the shell or container 5 with any desired fluid 11.

In Fig. 2 a modified form of the device is shown. In this instance the tube 9 is dispensed with and the shell or container 5 is provided upon its lower side with an opening 12 and an annular flange 13 which is preferably externally screw-threaded for the reception of a cap 14 of aluminum or other desired metal or glass of different kinds.

By this construction it will be apparent that the annular chamber 8 containing any desired liquid or solution will serve to absorb the heat generated by the cathode during the process of radiography. Furthermore, the objectionable rays emanating from the tube will be absorbed by any suitable fluid or solution surrounding the bulb 1.

In the structure shown in Fig. 2 the cap 14 may be used for filling the space between the bulb 1 and shell or container 5. Furthermore, certain additional objectionable rays may be taken up by the material of the cap which may be formed of any desired thickness of aluminum, silver, iron, glass or any other material desired. In both forms the cooling effect of the surrounding fluid on the entire tube is marked.

Having thus described my invention what I claim is:

1. In combination with an X-ray tube comprising a bulb, a cathode and an anode, a cooling and filtering fluid, and means for maintaining said fluid around said bulb.
2. In combination with an X-ray bulb containing a cathode and an anode, a cooling and filtering material surrounding said bulb, and means for maintaining said material in an operative position.

3. In combination with an X-ray bulb containing a cathode and an anode, a cooling and filtering material surrounding said bulb, and means for maintaining said material in an operative position; said means comprising a container for said material and spaced apart from said bulb.
4. In combination with an X-ray bulb containing a cathode and an anode, a cooling and filtering material surrounding said bulb, and means for maintaining said material in an operative position; said means comprising a container for said material and spaced apart from said bulb and closed at one end by the cathode and at the other end by the anode.
5. An X-ray tube comprising a bulb provided with a cathode and an anode, a closed shell spaced from and surrounding said bulb, and a cooling and filtering fluid in said shell; one end of said shell surrounding and closed by said cathode and the other end surrounding and closed by said anode.
6. An X-ray tube comprising a bulb provided with a cathode and an anode, a shell spaced from and surrounding said bulb and adapted to contain fluid for cooling said cathode and said bulb; said shell being substantially oval in shape and closed at the ends by having one end encircle the cathode and the other end encircle the anode.
7. An X-ray tube comprising a bulb provided with an anode and a cathode, a shell spaced from and surrounding said bulb and adapted to contain fluid, and means for filling the space between said bulb and said shell, said means comprising a removable cap connected with said shell, said cap also serving as a filter.
8. An X-ray tube comprising a bulb provided with an anode and a cathode, a shell spaced from and surrounding said bulb and adapted to contain fluid, and means for filling the space between said bulb and said shell, said means comprising a removable cap secured upon a flange formed on said shell, said cap also serving as a filter.
9. An X-ray tube comprising a bulb provided with an anode and a cathode, a shell spaced from and surrounding said bulb and adapted to contain fluid, and means for filling the space between said bulb and said shell, said means comprising a removable cap screw-threaded upon a flange formed on said shell, said cap also serving as a ray filter.
10. In combination with an X-ray tube comprising a bulb, a cathode and an anode, a fluid container surrounding said bulb and a cathode cooling and X-ray filtering fluid in said container.
11. In an X-ray tube having a bulb, a cathode tube and an anode tube, a fluid container surrounding said bulb, one end of said container surrounding and closed by the
- cathode tube and the other end surrounding and closed by the anode tube, and a cathode cooling and X-ray filtering fluid in said container.
12. In an X-ray tube having a bulb, a cathode tube and an anode tube, a fluid container surrounding said bulb, one end of said container surrounding and closed by the cathode tube and the other end surrounding and closed by the anode tube, a cathode cooling and X-ray filtering fluid in said container, and means for inserting and removing said fluid.
13. An X-ray tube comprising a bulb, a cathode, an anode, a shell surrounding said bulb, and a cap in said shell; said cap being adapted to absorb deleterious or objectionable rays of low penetrating power.
14. An X-ray tube comprising a bulb provided with a cathode and an anode, a shell surrounding said bulb, and a removable cap; said cap being adapted to permit of access to the interior of said shell and to absorb soft rays generated in said tube.
15. An X-ray tube comprising a bulb, a cathode, a cathode tube, an anode, an anode tube, and a shell surrounding and spaced from said bulb and having one end closed by and connected with said cathode tube and the other end closed by and connected with said anode tube.
16. An X-ray tube comprising a bulb, a cathode tube, a cathode, an anode tube, an anode, a shell surrounding and spaced apart from said bulb and having one end closed by and connected with said cathode tube and the other end closed by and connected with said anode tube, and a cooling and filtering material intermediate of said bulb and shell.
17. An X-ray tube comprising a bulb, a cathode and a cathode tube, an anode and an anode tube, and a shell surrounding and spaced from said bulb and having one end connected with and closed by said cathode tube and the other end connected with and closed by said anode tube, and a cooling fluid in the space between said bulb and shell.
18. An X-ray tube comprising a bulb, a cathode and a cathode tube, an anode and an anode tube, and a shell surrounding and spaced from said bulb and having one end connected with and closed by said cathode tube and the other end connected with and closed by said anode tube, and a removable window in said shell.
19. An X-ray tube comprising a bulb provided with an anode and a cathode, a shell spaced from and surrounding said bulb and adapted to contain fluid for cooling said cathode and said bulb; one end of said shell encircling and being closed by the anode and the other end encircling and being closed by the cathode.
20. In an X-ray tube having a bulb, a

cathode tube and an anode tube, a fluid container surrounding said bulb, one end of said container surrounding and closed by the cathode tube and the other end surrounding and closed by the anode tube, a cathode cooling and X-ray filtering fluid in said container, and a removable cap in said container, said cap also serving as a filter.

21. In an X-ray tube having a bulb, a cathode tube and an anode tube, a fluid container surrounding said bulb, one end of said container surrounding and closed by the cathode tube and the other end surrounding and closed by the anode tube, and means within said container for cooling the bulb and the cathode and preventing the production of soft rays.

22. In an X-ray tube having a bulb, a cathode tube and an anode tube, a fluid container surrounding said bulb, one end of said container surrounding and closed by the cathode tube and the other end surrounding and closed by the anode tube, and means between said container and said bulb for cooling the bulb and the cathode and maintaining a maximum vacuum in said bulb to prevent the production of soft rays.

In testimony whereof I hereto affix my signature in the presence of two witnesses.

ISAAC SETH HIRSCH.
